UNITED STATES PATENT OFFICE.

GEORGE MORRELL, OF LEOMINSTER, MASSACHUSETTS.

UMBRELLA TIP.

Application filed August 30, 1921. Serial No. 496,867.

To all whom it may concern:

Be it known that GEORGE MORRELL, a citizen of the United States of America, residing at Leominster, in the county of Worcester and State of Massachusetts, has invented certain new and useful Improvements in Umbrella Tips; and I do hereby declare that the following is a full, clear, and exact description of the same, such as will enable others skilled in the art to which it appertains to make and use the same.

This invention relates to improvements in umbrella tips, having for an object to provide a novel form of umbrella tip of such shape as will permit the same, together with like tips upon the free ends of the umbrella ribs, to be arranged in snug uniform relation whereby to constitute a substantially cylindrical body, in order that locking rings 20 may be engaged therewith for securing the various tips or segments constituting the body, in their juxtaposed relation.

It is also an object of the invention to provide a novel tip for umbrella ribs, which 25 will lend to the appearance of an umbrella provided with the same, particularly, when the umbrella is collapsed, and also, will permit the securing of the ribs in their innermost positions whereat they will be prevented from catching in the wearing apparel of a user.

Other objects will be in part obvious, and in part pointed out hereinafter.

In order that the invention and its mode 35 of application may be readily understood by persons skilled in the art, I have, in the accompanying illustrative drawings, and in the detailed following description based thereon, set out one embodiment of the same.

Figure 1 is a fragmentary view of an umbrella, showing the arrangement of the rib tips in their juxtaposed relation and secured by the locking ring.

Fig. 2 is a fragmentary side elevation of 45 the same.

Figure 3 is a fragmentary longitudinal section taken on the line 3—3 of Figure 2;

Figure 4 is a transverse section taken on the line 4—4 of Figure 3;

Figure 5 is a detail in perspective of one of the improved tips; and,

Figure 6 is a fragmentary detail partly in section, showing the engagement of the locking ring with a portion of one of the 55 tips.

Having more particular reference to the

drawings, in connection with which like characters of reference will designate corresponding parts throughout, I have shown, for purposes of illustration, my improved 60 form of tips arranged upon the outer or free ends of the ribs *r* of an umbrella, the covering of which is indicated by *c*, while the handle thereof is designated at *h*, the handle, preferably, being circular in cross 65 section and slightly tapered, as shown in Figures 1, 2 and 3.

A plurality of the improved tips are employed in connection with a single umbrella, and inasmuch as each of the same are 70 of identical construction and design, I will hereinafter refer to but one thereof for purposes of convenience.

The improved tip comprises a body portion including a tapered neck portion 1 having a tip proper, 2, formed on its outer portion, which tip, as will be noted, has the opposite side walls thereof bevelled or mitred as at 3, while the top wall thereof is flat. For purposes of ornamentation, that 80 is to improve the appearance of the tip, I may and preferably do curve the outer end and lower wall of the tip 2, as indicated at 4, thus rendering the same attractive with the opening of an umbrella equipped therewith.

In order that the tip may be firmly secured in position upon the outer end of the umbrella rib *r*, a transverse opening 5 is formed adjacent the inner end of the neck 90 1, and is adapted to be stitched to the outer portion of the umbrella covering *c*, as at 6; the neck 1, of course, being firmly engaged over the outer end of said rib *r*.

Right angularly disposed lugs or stops 7 95 are formed upon the outer sides of each of the necks 1 at points adjacent the inner ends of the flat top walls of their respective body portions and serve as means for limiting sliding engagement of the locking ring 8 100 thereover, which ring, as shown in Figures 1 and 2, is engaged over the various tips of the umbrella, when the same have been arranged in their juxtaposed relation.

The tips, when engaged with the umbrella 105 ribs *r*, are arranged so that their flat top or outer walls are arranged outermost, while the curved walls 4 thereof will lie adjacent the umbrella staff or rod *s*, as clearly shown in the Figure 3; said flat walls being arranged 110 substantially flush with the peripheral surface of the umbrella handle *h* in order that

said locking ring may be freely slid therefrom over the tips into engagement with stops 7 thereof. As will be noted, when the various tips 2 are in their juxtaposed relation they will, by reason of their bevelled or mitred walls, be permitted to have snug engagement with each other and thus constitute a substantially cylindrical body over which the locking ring 8 is to be engaged. Obviously, with the tips 2 in their juxtapositions, they will be prevented from catching in the wearing apparel of a user during carrying of an umbrella, and likewise will be prevented from catching in any other foreign matter or objects, since the ribs 7 will be secured in their innermost positions. Furthermore, the arrangement of the tips is such as will provide a novel and ornamental finish for an umbrella so equipped, and instead of the bulky arrangement now provided by the forms of ornamental tips now prevalent, a compact, neat, and attractive arrangement will be provided.

When it is desired to raise or extend the umbrella to its open position, the ring 8 is slid from over the tips 2 upwardly on to the tapered handle *h*, in which position it will remain until again used for locking the tips 2 in their juxtaposed relation.

It is to be understood that I do not confine myself to the peculiar design of tip herein illustrated, nor to a specific type of locking ring employed, the essence of the invention residing, primarily, in the provision of umbrella tips so shaped as to permit their juxtapositioning whereby to produce a body having continuity of surface, the various elements or segments of which may be held in their juxtaposed relation by any suitable form of means, such as conditions or preference may indicate.

Manifestly the construction shown is capable of considerable modification and such modification as is within the scope of my claims, I consider within the spirit of my invention.

I claim:

1. In combination with an umbrella, tips engaged with the ribs thereof, said tips being formed to permit of juxtapositioning of the same when the ribs are in their collapsed positions, whereby to produce a substantially cylindrical body.

2. In combination with an umbrella, tips engaged with the ribs thereof having their body portions formed to permit of juxtapositioning of the same when said ribs are in collapsed position, whereby to produce a substantially cylindrical body, and means engageable over the tips forming a substantially cylindrical body, whereby to secure the same in their snug relative position.

3. In combination with an umbrella, tips engaged with the ribs thereof having their body portions elongated and the side walls of the same mitered, whereby to permit of juxtapositioning of the same when the ribs are in their collapsed position for producing substantially cylindrical body, and means engageable over said elongated body portions for securing the same in their snug relative positions.

4. An umbrella tip comprising an elongated body portion having the side walls thereof mitered, a substantially cylindrical neck extending from one end of said body portion formed with a socket, and a stop on said neck adjacent its point of jointure with said body portion.

In witness whereof I have hereunto set my hand.

GEORGE MORRELL
